UNITED STATES PATENT OFFICE.

JOHN M. HAMILTON AND PEARLE A. BUOY, OF LOS ANGELES, CALIFORNIA.

ROLLER-BEARING SPRING-INSERT.

1,313,183.

Specification of Letters Patent.

Patented Aug. 12, 1919.

Application filed May 2, 1918. Serial No. 232,117.

To all whom it may concern:

Be it known that we, JOHN M. HAMILTON and PEARLE A. BUOY, both citizens of the United States, residing at Los Angeles, in the county of Los Angeles, State of California, have invented new and useful Improvements in Roller-Bearing Spring-Inserts, of which the following is a specification.

10 This invention relates to anti-friction means inserted between the leaves of springs such as are used upon automobiles, railway carriages and other vehicles. The primary object of this invention is to reduce friction generated by superimposed leaves of springs sliding upon one another.

The particular objects of this invention are to provide a device of such construction as to be almost invisible, practically dust proof, flexible enough to readily conform to the movement of the spring leaves, easily installed in springs already in service, which will act as an oil retainer, which is positively anchored in position, and which reduces 25 spring friction to a minimum.

We accomplish these objects by means of the embodiment of our invention illustrated in the accompanying drawing, in which:

Figure 1 is an enlarged side elevation of 30 an insert partly in section. Fig. 2 is a plan view of Fig. 1. Fig. 3 is a side elevation partly in section of a spring having inserts therein. Fig. 4 is a plan view of the spring shown in Fig. 3. Fig. 5 is an enlarged section as seen on the line 5-5 of Fig. 3.

Referring more particularly to the drawing, the spacing member is indicated generally by 6. It consists of a web 7 and side flanges 8 constructed preferably of flexible 40 sheet metal. The side flanges are bent upwardly from the web and then downwardly. Slots 9 are cut in the flanges to make the same flexible and also serving as anchoring means to engage the spring clips.

45 The upward extension of the side flange is designed to reach the upper leaf of a spring and the lower bend to overlap the lower leaf.

Lips 10 are cut and pressed from the web 50 forming slots in which rollers 11 are disposed and retained in place by the lips. These slots are disposed between the flange slots, thus, maintaining the insert at its maximum strength. The rollers do not extend 55 the full length of the web as will be noted from Figs. 1 and 2. It has been found by

experiment that it is unnecessary to extend the rollers to a very great distance from the outside ends of the leaves, as practically all the friction is generated at the ends. For 60 this reason the inserts are made short and anchored in position between the leaves. The upward bend of the side flanges with the lips 10 forms an oil retainer.

Referring particularly to Figs. 3, 4, and 65 5, the leaves 12 of a spring have clips 13 for clamping together the ends of the same. The inserts are placed between the leaves 12 so that the ends containing the roller bearings extend to the outside edges of the 70 leaves. The flanges adjacent the clips and upon both sides thereof are bent outwardly as indicated by 14 to form anchoring projections engaging the clips and preventing displacement of the inserts.

75 The inserts may be installed in springs already in use on cars by merely removing the spring clips 13, spreading the leaves 12 apart and inserting the inserts with the roller ends outward and even with the ends 80 of the leaves. The clip is now replaced, and the sections of the flange adjacent the clips bent outwardly, thereby firmly securing the inserts in position. In some cases the rollers will necessarily extend inside as well as outside of the spring clips. The friction of 85 the spring leaves between which an insert is placed grip the flat end of the insert and assist in holding it in position. The side flanges also serve to hold the insert in alignment.

90 The rollers are housed in the spring insert in a substantially dust proof cage. The cage also acts as an oil retainer. The insert is positively held in alignment and against 95 endwise displacement. It will also be noted that the insert is self contained, and in installing the same it is not necessary to place the rollers in position in the cage, the latter having the rollers already in position.

100 What we claim is:

1. An anti-friction device for interposition between the leaves of springs comprising a spacing member, and an anti-friction member journaled in said spacing member, 105 said member having slotted flexible side flanges forming tongues for co-operation with a clip so as to provide anchoring means to secure said member to the spring against endwise displacement.

110 2. An anti-friction device for interposition between the leaves of springs compris-

ing a spacing member, and an anti-friction member journaled in said spacing member, said spacing member being provided with flexible side flanges and having retaining 5 projections adapted to be disposed behind clips.

3. An anti-friction device for interposition between the leaves of springs comprising a spacing member, and an anti-friction 10 member journaled in said spacing member, said spacing member having slotted flexible side flanges extending above and below the web so as to provide retaining projections adapted to be disposed behind clips.

15 4. An anti-friction device for interposition between the leaves of springs comprising a spacing member, and a roller journaled in said spacing member, said spacing member being provided with flexible side flanges 20 and having anchoring means thereon to se-

cure said spacing member to the spring against endwise displacement, the web of said spacing member being slotted and having retaining lips upset therefrom to form a cage for the roller.

25

5. An anti-friction device for interposition between the leaves of springs comprising a spacing member, and a roller journaled in said member, said spacing member comprising flexible side flanges extending above and below the web thereof and having retaining projections adapted to be disposed behind clips, the web of said spacing member being slotted and having retaining lips upset therefrom to form a cage for the 30 35 roller.

In witness that we claim the foregoing we have hereunto subscribed our names.

JOHN M. HAMILTON.
PEARLE A. BUOY.
